(No Model.)

W. J. BENNINGTON.
WASHING MACHINE.

No. 449,995.

Patented Apr. 7, 1891.

UNITED STATES PATENT OFFICE.

WILLIAM J. BENNINGTON, OF ROXTON, TEXAS.

WASHING-MACHINE.

SPECIFICATION forming part of Letters Patent No. 449,995, dated April 7, 1891.

Application filed December 17, 1890. Serial No. 374,954. (No model.)

To all whom it may concern:

Be it known that I, WILLIAM J. BENNINGTON, a citizen of the United States of America, residing at Roxton, in the county of Lamar 5 and State of Texas, have invented certain new and useful Improvements in Washing-Machines, of which the following is a specification, reference being had therein to the accompanying drawings.

10 My invention pertains to an improvement in washing-machines which is designed to simplify the operation and to permit the pressure upon the fabric or each separate article to be adjusted or regulated by the judgment of 15 the person operating the machine, in order to permit all fabrics and the finest and costliest fabrics to be thoroughly cleansed without any greater detriment thereto than if washed by the hands; and it consists in the 20 novel construction, combination, and arrangement of the parts, substantially as hereinafter described, and shown in the accompanying drawings, in which—

Figure 1 is a vertical section of my washing-machine. Fig. 2 is a plan broken view thereof, the rubber being removed. Fig. 3 is a plan view of the rubber, and Fig. 4 is a broken detailed sectional view of the rubber and the roller-surface immediately thereunder.

30 In constructing my washing-machine I first erect the supporting-frame A, which consists of the four standards *a a* and the cross-standard connecting-pieces *b b* and *b' b'*. The standards of frame A may be secured together laterally or at either end thereof by means of 35 nutted bolts in lieu of cross-bars *b' b'*.

C C, &c., are rollers, having their reduced ends journaled in circular recesses in the upper connecting-pieces *b b*, and they form the 40 surface upon which the clothes are rubbed. Immediately below the series of rollers the

board *d* is attached to the lower connecting pieces, and this board forms the support for the tub, which is secured thereupon in any suitable manner, as shown in dotted lines in 45 Fig. 1.

To the frame A is bolted or rigidly secured in any ordinary manner the vertical bar *d*, terminating at top in the rounded stud or projection *d'*, which is adapted to correspond 50 with orifice *e* in the rubber *f*, through which it projects, the latter in practice being pivoted thereon. The rubber *f* is provided with a series of closely-arranged longitudinal spiral springs *g*, adapted to occupy parallel planes 55 with the rollers *C C*, the ends of the wires of said springs being connected to said rubber in any suitable manner.

In practice the article to be washed is placed upon the rollers above the tub, and by 60 swinging the rubber horizontally the springs thereof are caused to impart an elastic suitable or requisite degree of pressure upon the clothes, the machine thus being rendered efficient and rapid in operation. 65

Having thus fully described my invention, I claim—

The washing-machine having the tub-supporting frame, provided with a series of rollers arranged just above and centrally of the 70 tub, and the horizontal swinging rubber, one end pivoted upon a standard suitably supported upon said frame and having the series of closely-arranged longitudinal spiral springs arranged to occupy parallel planes with said 75 rollers, substantially as set forth.

In testimony whereof I affix my signature in presence of two witnesses.

W. J. BENNINGTON.
